UNITED STATES PATENT OFFICE.

JOHN E. MEGLEMRE, OF LINCOLN, NEBRASKA.

MECHANICAL MOVEMENT.

1,149,389.

Specification of Letters Patent. Patented Aug. 10, 1915.

Application filed January 21, 1913. Serial No. 743,401.

To all whom it may concern:

Be it known that I, JOHN E. MEGLEMRE, a citizen of the United States, residing at Lincoln, in the county of Lancaster and State of Nebraska, have invented an Improvement in Mechanical Movements, of which the following is a full, clear, and exact description.

This invention relates to cam mechanism for converting continuous rotary motion into reciprocating rectilinear motion and is adapted for use in various types of machinery in which the reciprocating members offer constant resistance in one direction of their movement and are impelled with constant force in the opposite direction of their movement.

The object of this invention is to reduce to a minimum the variations in resistance to the driving force resulting from the use of a limited number of cams upon a drive shaft for reciprocating such members, thereby eliminating irregular and jerky movements and consequent wear and tear upon the driving parts, insuring smooth and noiseless operation, and increasing the general efficiency of the machine.

One embodiment of my invention in which these objects are attained is illustrated in the accompanying drawings, in which—

Figure 1 is a perspective view of a double cylinder lift pump in which the plungers are driven by the improved cam mechanism. Fig. 2 is a diagrammatic view of the cam, showing their relative arrangement and the position of the rollers actuated by the cams. Fig. 3 is a face view of the cam shown in Fig. 2.

In the accompanying drawings which show the improved cam mechanism applied to the driving shaft of the pump, the stationary support 1 has pivoted thereto, near its upper end, two swinging levers, 2 and 3. Pivotedly connected to the swinging levers 45 toward their outer ends are two upright rods, 4 and 5.

Connected to the upright rods, at their upper ends, are the pump rods, 6 and 7, which operate in the pipes, 8 and 9.

Upon the outer ends of the swinging rods, 2 and 3, are provided rollers, 10 and 11, which travel upon the faces of the cams, 12 and 13. The cams 12 and 13 are attached to opposite faces of a disk, 14, which is fixed upon a shaft, 15. The shaft, 15, has a sprocket wheel, 16, fixed upon one end and

is driven from any suitable source of power, such as a water wheel, 17.

The cams, 12 and 13, as clearly shown in Fig. 2, are each double armed cams, equal to size and shape, and are arranged with the faces of one of them ninety degrees in advance of the corresponding faces of the other, whereby each of the arms, 2 and 3, is elevated twice in one revolution of the shaft, 15, and alternate reciprocating motion is transmitted to the pump rods.

Referring again to Fig. 2, each cam comprises two equal arms, 18 and 19, and each arm has an outwardly curved lifting face, 20, and an outwardly curved lowering face, 21. The lowering face of one arm is connected with the lifting face of the other by an inwardly curved portion, 22, and the lifting face of each arm is connected with its lowering face by a sharply curved portion, 23. The lifting face of the cam has a rapidly increasing curvature in that portion leading away from the inwardly curved portion, 22, reaching the point of greatest curvature near the inner end of the arm, from which point the curvature gradually decreases toward the outer end of the arm. Near the outer end of the arm, the curvature of the lifting face again begins to increase until the sharply curved portion, 23, at the end of the arm, is reached. The curvature of the lowering face gradually decreases from the outer end of the arm toward the inner end.

The rollers, 10 and 11, are arranged to move in a nearly vertical path, a little to that side of the shaft, 15, toward which the cams move. In the type of pump shown, where the pump rod is lifted by the cam and returns by gravity, the rollers will press against the cam at all portions of their movements, but when desirable, guides may be attached to the disk along portions or entirely around the periphery of the cam, forming with the cam faces slots for the rollers to travel in.

It will be seen, from the above description, that as the lifting face of the cam moves toward a roller, causing the roller to pass from the inwardly curved portion, 22, to the steep portion of the lifting face, the roller will be raised with increasing velocity until the point of greatest curvature is reached, whereupon the roller will be elevated with uniform speed until near the outer end of the arm, where, on account of

the increasing curvature, the speed is gradually lessened preparatory to beginning the downward movement. The downward run is so curved that the roller will be permitted 5 to travel for a short distance with an accelerated movement and then with uniform velocity to nearly the lower end of its stroke, when it is caught up and retarded by the inwardly curved portion, 22. By reason of 10 this arrangement, during the greater portion of the upward stroke, a very nearly constant lifting force is applied to the roller by the cam, and during the downward or return stroke, the roller by reason of the weight 15 which it carries, will exert a nearly constant turning force upon the cam. When the two cams are arranged as shown in Fig. 2, the constant force applied to the ascending rod is counterbalanced by the constant force due 20 to the weight of the descending rod upon the lowering face of the cam, so that at all times except at the end of the strokes a constant load is imposed upon the driving shaft. 25 It will be observed from Fig. 2 that the lifting face, 20, of each arm of the cam is longer than the corresponding lowering face, 21, and consequently it will be seen that the cam turns through an arc of more than ninety degrees in lifting the roller, and 30 through an arc of less than ninety degrees in lowering the roller, so that the rod will fall with greater velocity than it has during the upward stroke. The main object of this, however, is to maintain an equal load upon 35 the driving shaft during the change in direction of the strokes of the two rods. The outer end of each arm of the cam is so curved that the velocity of the pump rod will be gradually decreased when it ap- 40 proaches the upper end of its stroke, and the inwardly curved portion, 22, is so curved that as the rod approaches the lower end of its stroke its velocity will be gradually checked and an accelerated movement will 45 be given to the rod at the beginning of its upward stroke. It will be seen that, as the upward movement of one rod begins to slacken and its resistance to the driving force is lessened, the other rod will have begun its 50 upward movement, imposing a load upon the driving shaft which increases as the load, due to the other rod, decreases, thereby enabling the pump rods to change from

their upward strokes to their downward strokes, and from their downward strokes 55 to their upward strokes without causing a variation in the load imposed upon the drive shaft.

It will be seen from the above that means have been provided whereby two pump rods 60 may be actuated from a drive shaft by means of cams, substantially without variation in the resistance to the driving force.

It will be understood that the curvature of the various portions of the cam will depend, somewhat, upon the conditions to be met with in the particular machine in which the cam mechanism is to be used, such as the ratio of the force exerted by the cam upon the reciprocating member in one direction 65 to the force exerted by the reciprocating member upon the cam in the other direction. However, from the above disclosure, any one skilled in mathematics and familiar with the principles of mechanics, can compute the curvature of the above described portions of the cam for the particular machine in which it is intended to be used. 75

I do not wish to limit myself to the exact construction shown, but believe myself to be 80 entitled to vary the same within the scope of the appended claim.

What I claim as my invention and desire to secure by Letters Patent is:

In mechanism of the character described, 85 a shaft, a disk mounted upon the shaft, cams carried by the shaft and seating flatly against opposite sides of said disk and disposed within the lines thereof, the disk forming a plate separating the cams, each of 90 said cams including a neck receiving the shaft and having enlarged relatively offset diametric radial arms formed thereon extending in opposite directions relative to the plane of the neck, the arms of each of said 95 cams having oppositely presented sinusoidal outer edges intersecting at the points of the arms with the depressions of the edges of the arms of each cam arranged opposite each other at the neck therebetween. 100

In testimony whereof I hereby affix my signature in the presence of two witnesses.

JOHN E. MEGLEMRE.
